(57) **CLAIM**

The ornamental design for a hair dryer, as shown and described.

DESCRIPTION

FIG. 1 is a front view of a hair dryer, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof;

FIG. 9 is a perspective view thereof; and,

FIG. 10 is another perspective view thereof, shown with the stand in extended condition.

The broken line shown in the drawings are for the purpose of illustrating portions of the article and form no part of the claimed design.
